WORK HOLDER MECHANISM

Ira C. Maxwell and Ole H. Langen, Minneapolis, Minn., assignors to The Unipress Company, Incorporated, Minneapolis, Minn., a corporation of Minnesota

Application December 15, 1947, Serial No. 791,850

7 Claims. (Cl. 38—12)

1

This invention relates to work holders for laundry presses and the like having a pressing buck and a presser head movable into and out of pressing engagement therewith. In such pressing machines the garment which is usually in a damp condition is laid on the buck and the presser head is engaged for the pressing operation. In the pressing of flat work such as shirt fronts and backs, it is important to maintain the work flat and free from wrinkles, and to this end various work holders have been devised.

It is an object of the invention to provide an improved work holder which, of course, performs its intended function of holding the work flat and one that is agile in its operation and capable of moving or being moved quickly to and from its operating position. It is also an object to provide an improved work holder which is light in weight, easily operated, yet strong and positive in action, attractive in appearance and having good operator acceptance and reasonably automatic in its operation, yet not too complicated.

Other objects of the invention are those inherent in the apparatus herein illustrated, described and claimed.

The invention is illustrated with reference to the drawings in which:

Figure 1 is a partial front elevational view of a pressing machine showing the presser head in engagement with the buck and showing a front elevational view of the work holder of the present invention in work holding positions;

Figure 2 is also a partial front elevational view of the pressing machine of Figure 1, but with the presser head raised and the work holder moved to the out-of-the-way position;

Figure 3 is a fragmentary sectional view of the attachment of the work holder band to one of the bifurcated end pieces of the work holder stem. Figure 3 is taken in the direction of arrows 3—3 of Figure 2;

Figure 4 is a sectional view taken in the direction of arrows 4—4 of Figure 1 and shows the separated operating mechanism of the work holder;

Figure 5 includes a rear elevational view of the work holder parts in their work-engaging position. In this view some of the parts of the work holder are broken away and the view is somewhat enlarged. Figure 5 also includes a portion of the presser arm and the air lines and valve and valve operating mechanism.

Figure 6 is a fragmental section taken in the direction of arrows 6—6 of Figure 2 and shows a

2

side view of the bifurcated ends on the work holder stem.

Throughout the drawings corresponding numerals refer to the same parts.

5 Referring to the drawings, the pressing machine includes a main frame 10 supporting the work table 11 and buck support 12 upon which buck 13 is mounted. Presser arm 14 is pivotally mounted at 15 on the rear uprights 16 (Figure 5) 10 of the main frame and serves to carry the presser head 18 which is thereby moved into and out of engagement with the buck 13. The press operating mechanism is connected at pivots 19 and 20 on the presser arm and are not shown since they, per se, form no part of the invention. Closed press position of the presser arms 14 is shown in full lines. Any suitable press operating mechanism may be used.

Upon the main frame member 21 there is 20 mounted the work holder frame casting 22 which is suitably attached to the frame 21 by bolts 24. The work holder frame 22 overhangs the main frame 21 at the right side as shown in the front view (Figure 1) and carries a pivot shaft 25 that 25 is pivotally mounted in journals 26—26 on the work holder frame. In the space between journals 26 and 26 a work holder stem 28 is attached solidly to shaft 25, either by a key, set screw or other suitable device, so that when the stem 28 30 is moved pivotally in the direction of arrows 30 or 31, shaft 25 is also rotated.

The stem 28 of the work holder assembly extends upwardly and works in a slot 22 in the table 11 at a position almost immediately under the center line and at one end of the buck 13. At the joint 34 there are solidly attached a bifurcated end of the work holder device, this bifurcated end being composed of a front portion 35 (Figures 1 and 2) and back portion 36 (Figure 4) 5) which extend, respectively, forwardly and rearwardly to positions so as to clear the front and back edges of the buck 13 when the work holder stem and bifurcated end structures 28—35—36, see Figure 6, which moves as a unit, is swung from the out-of-the-way position of Figure 2 to work engaging position of Figure 1.

To the ends 35 and 36 there are attached a band 38 which is held by bolts 39. At least one end of the band is slotted where the bolts pass 50 through so as to allow the band to move a limited amount endwise in respect to the members 35 and 36. The band 38 is stabilized against flapping by one or more clips 42 which engage one edge of the band and force it into engagement with a fixed (stabilizing) surface on the end

of the member 36, yet the construction permits the band 38 to slide a limited amount.

The frame 22 of the work holder has an end upright 43 which serves as a pivot support at 44 for the base 45 of cylinder 46, which is, therefore, free to oscillate about pivot 44. Cylinder 46 has a piston 47 and piston rod 48, the latter being pivoted at 49 to the stem 28. Cylinder 46 is vented at 50; hence permits only a limited working stroke on piston rod 48 which is enough to move the work holder against the action of the retaining mechanism 56-61, hereinafter described, and start the stem 28 and the work holder assembly in its arcuate travel in the direction of arrow 30 (Figure 1). Once this occurs the work holder is free moving and continues until stem 28 engages buffer 52 which is mounted on outwardly extending portion 53 of the work holder frame 22.

The retaining mechanism of the work holder includes a lever 54 which is pinned or keyed to shaft 25 so as to move when the work holder 28-35-36 moves. Lever 54 has a side shaft, detent shaft, or projection 55 which carries roller 56 which, therefore, moves in an arcuate path of travel denoted by dotted line 58.

Upon the work holder frame there is an up-standing slotted post 60 upon which the detent lever or plate 61 is pivoted at 62. Lever 61 has a slot 64 in it in which a roller 65 rolls. The roller journal shaft 66 has a spring attached at each end (springs 67 and 68) and these are tensioned as a pair and attached to eye bolts 79 and 71. The position of slot 64 in lever 61 is such that the roller tends to roll in slot 64 in the direction of arrow 72 when the work holder is brought to the engaging position of Figure 1 and tends to roll in the direction of arrow 74 when lever 61 tilts due to the movement of the work holder to the position of Figure 2.

The movement of lever 61 is occasioned by the action of roller 56 in entering and moving in an open ended slot 75 in lever 61. Lever 61 moves to the position shown in Figure 2 and is stopped by the adjustment screw 76 which engages ledge 77 of frame piece 60. The screw 76 may be adjusted so that when springs 67 and 68 pull the lever 61 to the Figure 2 position, the slot 75 of lever 61 will have its center line aligned with the arcuate path of travel of roller 56 on lever 54.

Shaft 25 is also provided with an arm 78 which is pinned or keyed to the shaft 25 so as to move with it. Arm 78 is mounted so that when the work holder mechanism is in the Figure 1 position, the arm 78 will nearly engage the head of adjustable stop screw 79 which is threaded into frame 22. The screw 79 serves to limit movement of the work holder mechanism in the direction of arrow 31.

Upon the machine frame upright 16 there is mounted a valve 80 which has an operating stem 81 terminating in a flattened top 82 that is lifted in the valve closing direction by spring 84. Air supply line 85 extends through reducer valve 86 and thence via line 87 to the valve 80. From valve 80 a line 88 extends through manual metering control valve 89 and thence via hose 90 to connection 91 on cylinder base 45. On the presser arm or on any other oscillating portion of the pressing machine which moves in unison with the presser head, there is mounted a valve operator having base 92 to which arm 93 is pivoted at 94. The arm 93 is pulled in the direction of arrow 95 by spring 101 which is attached to the arm 93 and to base 92. Stop 97 limits this

movement. Yet arm 93 can move in the direction of arrow 96 against the action of spring 101. Arm 93 is provided with a roller 98 pivoted to the arm at pin 99.

Operation.—The press may be assumed to be open and the work holder is assumed to be in the position of Figure 2. The press operator then makes the lay of the garment on the buck 13 and after straightening out wrinkles, the operator grasps member 35, which acts as a handle, and swings the entire work holder assembly (28, 35, 36, 38) from the position of Figure 2 in the direction of arrow 31 toward the Figure 1 position of the work holder. This movement is free since cylinder 46 is ported and is uninterrupted until roller 56 enters slot 75, whence upon continued movement the lever 61 is moved by the action of roller 56 in slot 75 until the springs 67 and 68 are drawn up. Then, as the slot 64 and hence lever 61 is sufficiently tilted, the roller 65 rolls with a quick action from the inner end (Figure 2) to the outer end (Figure 1) and in so doing pulls the lever 61 in the same direction that roller 56 has up to that time been pushing the lever 61. Consequently, lever 61 then imposes a holding force on roller 56 and, as shown in Figure 1, the force of springs 67 and 68 which is transmitted to roller 65 and thence through lever 61 to roller 56 imposes a torque force on arm 54 tending to move arm 54 and hence the entire work holder in a direction such that the work holder is held firmly upon the garment. Then the operator closes the press by the usual controls.

In closing the press the roller 98 (Figure 5) which has been in the dotted line (or open press position) is moved to the full line position, but valve 80 is not actuated because the roller 98, upon engaging the flat top 82 of the operating stem, simply lifts a slight amount and moves arm 93 in the direction of arrow 96 against the action of spring 101 which is sufficiently weak so that it deflects and allows the roller 98 to move idly over top 82 without imposing on the top 82 a force sufficient to compress spring 84 and open valve 80.

When the pressing operation is completed the operator opens the press by manipulating the appropriate press controls and the presser head lifts and presser arm 14 moves in the direction of arrow 83 to open press position. In so doing roller 98 moves down along the path of dotted line 105 and engages head 82 and presses valve stem 81 down to open the valve 80, for in this movement the lever 93 is held by stop 97 and hence roller 98 operates with determination upon stem 81-82. However, the valve 80 is held open only a short time as the presser arm is moving from closed to open position.

The shot of air thus injected into line 88 and thence through valve 89 and line 90 to cylinder 46 is moderated by the manual control valve 89 so that the air exerts just sufficient force through piston 47 and piston rod 48, as previously described, to push the work holder stem 28 out of retention by the retaining mechanism (springs 67, 68, roller 64, lever 61, slot 75 and roller 56) and then with slight remaining force, flips the work holder stem 28 and members 35, 36 and 38 toward the position shown in Figure 2 where they come to rest against the buffer 52. Port 50 in the cylinder 46 allows the cylinder 46 to exhaust in this position. The movement of the work holder mechanism is very agile and yet is free from abuse to the mechanism itself, the buck of the press or to the operator.

As many apparently widely different embodiments of this invention may be made without departing from the spirit and scope thereof, it is to be understood that we do not limit ourselves to the specific embodiments herein except as defined by the appended claims.

What we claim is:

1. A work holder for a pressing machine having a machine frame, a generally horizontal transversely extending buck on the machine frame, said buck having front and back edges, a cooperating presser head, a movably mounted presser arm mounted on said machine frame and carrying said presser head to move the same into and out of pressing engagement with said buck, a pivot shaft mounted on the machine frame and extending transversely of the buck below it, a work holder stem extending outwardly from the pivot shaft and having a bifurcated end capable of clearing the front and back edges of the buck as the work holder stem is swung pivotally about the axis of the pivot shaft, a work contacting band attached to the ends of said bifurcated portions, said band being movable thereby into and out of engagement with the buck, an air cylinder having a piston and piston rod therein, said air cylinder and piston rod being connected to the frame and also to said stem and an inlet for air into the cylinder for moving the piston rod outwardly to thereby move the stem in a position to lift the band out of engagement with the buck, and a valve in said inlet for air normally closing the same, and valve operating means pivotally connected to said presser arm and movable in synchronism therewith and being located to engage and open said valve as said presser arm moves said presser head out of engagement with said buck.

2. The apparatus of claim 1 further characterized in that there is included a detent shaft pivotally mounted on said frame and supported below said transversely extending buck, said detent shaft being parallel to said work holder pivot shaft and adapted to travel through an arcuate path, rigid means interconnecting said mounting for said detent shaft and said work holder stem, said detent shaft thereby being operably responsive to movement of said work holder stem for moving said detent shaft through said arcuate path as the stem is swung from a position in which the work holder engages the buck to a position in which the work holder is remote from the buck, a lever having a bifurcated end portion pivotally mounted on said frame by pivot means extending parallel to said work holder pivot shaft for movement through a limited arc intersecting said arcuate path of said detent shaft whereby said bifurcated lever may move from a position in which the detent shaft can enter endwise into the bifurcated end portion of said lever and thence arcuately as the detent shaft continues to move, and an over center spring means anchored to said machine frame and connected to said bifurcated lever for urging the continued movement of said bifurcated lever for applying a holding force on work table 11 and buck support 12 upon which stem.

3. The apparatus of claim 2 further characterized in that the detent shaft is carried by a second lever on the pivot shaft.

4. A mechanism of the type described in claim 1 further characterized in that said presser head is carried by presser arms mounted by pivot means to said machine frame, said valve is mounted on said frame below one of said presser

arms and has an operating stem located below said presser arm, and said valve operating means consists of a pivoted arm mounted on said presser arm movable to a position such that it does not press the valve stem as the press operating means moves to close the presser head upon the buck and said pivoted arm is movable to a position such that the operating stem is moved to open the valve momentarily as the press operating means moves to open the press.

5. The apparatus of claim 1 further characterized in that said work contacting band is slotted at one end for attachment to one of the bifurcated ends on said work holder stem whereby said band may move a limited amount endwise with respect to said one of the bifurcated ends on said work holder stem.

6. A work holder for a pressing machine having a machine frame, a generally horizontal transversely extending buck on the machine frame, said buck having front and back edges, a cooperating presser head, a movably mounted presser arm mounted on said machine frame and carrying said presser head to move the same into and out of pressing engagement with said buck, a pivot shaft mounted on the machine frame and extending transversely of the buck below it, a work holder stem extending outwardly from the pivot shaft and having a bifurcated end capable of clearing the front and back edges of the buck as the work holder stem is swung pivotally about the axis of the pivot shaft, a work contacting band attached to the ends of said bifurcated portions, said band being movable thereby into and out of engagement with the buck, said apparatus also including a detent shaft pivotally mounted on said frame and supported below said transversely extending buck, said detent shaft being parallel to said work holder shaft and adapted to travel through an arcuate path, rigid means interconnecting said mounting for said detent shaft and said work holder stem, said detent shaft thereby being operably responsive to movement of said work holder stem for moving said detent shaft through an arcuate path as the stem is swung from a position in which the work holder engages the buck to a position in which the work holder is remote from the buck, a lever having a bifurcated end portion pivotally mounted on said frame by pivot means extending parallel to said work holder pivot shaft for movement through a limited arc intersecting said arcuate path of said detent shaft, whereby said bifurcated lever may move from a position in which the detent shaft can enter endwise into the bifurcated end portion of said lever and thence arcuately as the detent shaft continues to move, and an over center spring means anchored to said machine frame and connected to said bifurcated lever for urging the continued movement of said bifurcated lever for applying a holding force on work table 11 and buck support 12 upon which stem.

7. A work holder for a pressing machine having a machine frame, a generally horizontal transversely extending buck on the machine frame, said buck having front and back edges, a cooperating presser head, a movably mounted presser arm mounted on said machine frame and carrying said presser head to move the same into and out of pressing engagement with said buck, a pivot shaft mounted on the machine frame and extending transversely of the buck below it, a work holder stem extending out-

wardly from the pivot shaft and having a bifurcated end capable of clearing the front and back edges of the buck as the work holder stem is swung pivotally about the axis of the pivot shaft, a work contacting band attached to the ends of said bifurcated portions, said band being movable thereby into and out of engagement with the buck, a detent protection spaced from the pivot shaft and connected thereto and to the stem so as to be moved to and fro through an arcuate path as the work contacting band is moved into and out of engagement with the buck, a detent plate having an open-ended slot therein, a pivot spaced alongside said arcuate path and mounting said plate for pivotal movement intersecting the course of movement of said detent projection, a stop for holding said plate at a limiting position of pivotal movement with the open end of the slot generally aligned with said arcuate path of movement of the detent projection so that said projection can enter the slot when the work holder is moved toward work holding position, the detent plate being thereby

5 moved pivotally by the reaction of the detent projection in said slot, over-center spring means connected to the frame and to said detent plate for resiliently pivoting said detent plate towards said stop when the plate is pivotally moved to a predetermined intermediate position adjacent said stop and for pivotally urging said detent plate away from the stop when the detent plate is pivotally moved to a predetermined distance away from the stop, said detent plate thereafter being effective to urge the continued movement of said detent projection and work holder toward work holding position.
